CLAIM

The ornamental design for dual integrated circuit card reader/writer, as shown.

[21] Appl. No.: 174,315

DESCRIPTION

[22] Filed: Mar. 25, 1988

FIG. 1 is a top, front, left side isometric view of a dual integrated circuit card reader/writer showing my new design;

[52] U.S. Cl. D14/105; D14/107

FIG. 2 is a front elevational view thereof;

[58] Field of Search D14/100, 105, 107, 114,
D14/117, 109; D13/40; 235/379-382, 454, 455,
462-465, 470, 471, 479, 480; 483/487, 493, 441,
443; 361/331, 380, 390-395, 399; 369/106, 109,
275

FIG. 3 is a right side elevational view thereof;

FIG. 4 is a back elevational view thereof;

FIG. 5 is a left side elevational view thereof; and

FIG. 6 is a bottom plan view thereof.

FIG. 1

FIG. 2

FIG. 3

FIG. 4

FIG. 5

FIG. 6
